UNITED STATES PATENT OFFICE.

FREDERICK H. BERRY, OF MILWAUKEE, WISCONSIN.

DENTAL ENGINE.

SPECIFICATION forming part of Letters Patent No. 654,869, dated July 31, 1900.

Application filed July 14, 1899. Serial No. 723,784. (No model.)

To all whom it may concern:

Be it known that I, FREDERICK H. BERRY, of Milwaukee, in the county of Milwaukee and State of Wisconsin, have invented a new 5 and useful Improvement in Dental Engines, of which the following is a description, reference being had to the accompanying drawings, which are a part of this specification.

My invention has relation to improvements 10 in dental engines.

One of the objects of the invention is to provide an improved construction for regulating the length of the dental-engine standard in order to provide for readily taking up in- 15 equalities in the belt.

A further object resides in providing a spring for automatically taking up slack in the belt, in combination with means for increasing the tension of said spring, whereby 20 after the expansive power of the spring under a certain compression has become exhausted, and thereby the efficiency of the spring to further take up slack in the belt impaired, said spring may be further com- 25 pressed in order to be again serviceable as a means for automatically compensating for slackness and unevenness in the belt.

A further object resides in the improved construction of dental-engine head for permitting the flexible arm and the tool carried thereby to be readily turned down out of operative position or to be turned up and held in position for operation.

A still further object resides in the provi- 35 sion of an improved self-aligning bearing.

With the above and other incidental objects in view the invention consists of the devices and parts or their equivalents, as hereinafter more fully set forth and claimed.

40 In the accompanying drawings, Figure 1 is a front elevation of the complete device, showing the flexible arm in position for operation. Fig. 2 is an elevation at right angles to Fig. 1. Fig. 3 is a central section of the upper portion of the engine, showing the head and flexible arm carried thereby in operative position. Fig. 4 is an elevation of the upper portion of the engine, showing the head and the flexible arm and other parts 45 carried thereby adjusted downwardly out of operative position; and Fig. 5 is an end view of one of the self-aligning bearings.

Referring to the drawings, the numeral 11 indicates a base, preferably of tripod form, the legs of the tripod advisably having rollers mounted therein for convenience in moving the engine from place to place. This base has extending upwardly therefrom a supporting-stem 12, which supports a motor box or casing 42. The numeral 43 indicates 55 the motor-shaft, which extends outwardly beyond the side of the casing and carries a series of variable-sized pulleys 44.

Extending upwardly from the top of the motor box or casing is a supporting-column 65 45 for the dental-engine arms. This column is provided at its upper end with a tubular portion 46, and in the bore of this tubular portion is fitted the lower portion of the tubular post 47, an insulating-sleeve 48 being interposed between said post 47 and the tubular portion 46 of the standard, said sleeve having outwardly-flanged upper and lower ends, the flanged upper end fitting between the upper end of the tubular portion 46 and the under 70 side of a shoulder formed on the post 47 and the flanged lower end fitting between the lower end of the tubular portion 46 and a nut 49, turning on the lower threaded extremity 75 of the post 47. Extending through the post 80 47 is a rod 50. The lower end of this rod, which projects below the post 47, may be formed or provided with an enlargement for convenience in turning said rod. This enlargement is preferably in the form of a 85 milled wheel 51, which is advisably secured to the rod by means of a screw 52, extending through the wheel and impinging at its inner end against a flat or plane side of the rod. (See Fig. 3.) The upper portion of the rod 50, 90 which extends above the post 47, is threaded, as clearly shown in Fig. 3. In order to prevent the rod when turned from working downwardly, said rod is intersected by a cross-pin 53, which rests on the upper end of the post 95 47. Connected to the upper end of the post 47 is a sleeve 54, the connection being made, preferably, by screw-threads. The standard of the dental engine fits and telescopes into this sleeve 54. The lower end of the standard 100 is provided with a threaded opening which is engaged by the threaded portion of the rod 50, as clearly shown in Fig. 3. By the engagement described the dental-engine stand-

ard can be raised or lowered merely by turning the hand-wheel 51. This specific form of mechanism for adjusting the standard provides a simple means for raising or lowering 5 said standard, and which means can be employed in connection with foot-power dental engines, or, in fact, in connection with a variety of different forms of dental engines for the purpose of taking up slack and unevenness in the belt, due to stretching or otherwise.

I prefer to form the dental-engine standard just referred to of two telescoping sections, the lower section being indicated by the numeral 55 and the upper section by the numeral 56, said lower section being the portion 15 which fits in the sleeve 54. A spring 57 is arranged in the lower section 55, and the upper end of this spring bears against the lower end 20 of the upper section 56, while the lower end of the spring bears against a pin 58 or equivalent device extending across the bore of the lower section 55. As is well known to those familiar with this class of machines, the endless belt, which transmits rotation to the dental-engine tool, will stretch, and consequently 25 become slack. By constructing the standard of two telescoping sections and arranging the spring 57 as described provision is made for automatically taking up slack in the belt, due 30 to stretching of said belt. Inasmuch as the spring 57 constantly exerts an upward pressure on the upper section 56 of the standard said upper section is necessarily raised as soon as any slack of the belt occurs, and consequently 35 said slack is taken up. Of course after the spring has expanded to its full limit it can effect no further useful function in taking up slack in the belt; but by employing the rod 50 in connection with the two-part 40 standard and the spring referred to whenever the spring expands to its full extent then by merely turning said rod 50 the spring will be again compressed, and hence its expansive power increased, so as to render said spring 45 again capable of taking up the slack.

The numeral 59 indicates a slotted arm to which the dental-engine head is pivoted. This arm is provided with a depending rod 60, which extends for a desired distance into the upper 50 section 56 of the dental-engine standard. Surrounding the lower end of the arm 59 and the upper end of the section 56 of the standard is a slidable sleeve 61. The upper edge of this sleeve is rounded or beveled, as clearly shown 55 in Fig. 3. The interior of the sleeve is provided with a shoulder 62, which limits the upward movement of the sleeve. A coiled spring 63 is confined within the sleeve 61 and surrounds the rod 60, the end of said spring 60 being confined between the shoulder 62 and the upper end of a collar 64, which surrounds the rod 60 and forms a continuation of the upper telescoping section 56. This collar 64 is provided with a shoulder which forms a 65 stop to limit the downward movement of the sleeve 61.

The dental-engine head is indicated by the

numeral 65 and is preferably in the form of a yoke consisting of two arms merging at their lower ends into a downwardly-extending stem 70 66, said arms at the point of merging being pivoted to the upper end of the arm 59 by means of a pivot-pin 67. One of the lower corners of this stem is rounded or beveled off, as indicated by the numeral 68. The upper 75 ends of the arms of the dental-engine head form retaining-boxes for the bearings of the shaft which imparts rotation to the dental-engine tool, and said head also carries the dental-engine arm and the flexible arm or 80 sheath which surrounds the flexible shaft for driving the tool. When the engine is not in operation, the dental-engine head and the parts connected thereto are in the position shown in Fig. 4—that is to say, with the head 85 extending out horizontally from the arm 59 and the dental-engine arm and flexible arm extending downwardly in a straight line. When it is desired that the engine should operate, the dental-engine head is turned upwardly by hand and the rounded corner 68 of the depending stem 66 is brought into contact with the beveled upper edge of the sleeve 61, and said sleeve is moved downwardly against the action of the spring 63 to the extent permitted by the shoulder of the collar 64, and the stem then passes into the slot of the arm 59. The moment the stem reaches a vertical position in this slot with its end clear of the edge of the sleeve 61 the coiled spring 63 will 90 expand and force the sleeve 61 upwardly, so that its upper edge will surround the lower end of the stem 66, and thereby hold said stem in a locked upright position. In order to again bring the parts to the Fig. 4 position, the sleeve 61 is grasped by the fingers and 95 pressed downwardly against the action of the spring 63 until the upper edge of the sleeve 61 is below the lower end of the stem 66. The head 65 and its attached parts can then be 100 readily turned to the Fig. 9 position.

The upper ends of the arms of the head 65 are tubular or cylindrical, as indicated by the numerals 69 69, and in these tubular or cylindrical portions are arranged tubular bearings 115 70 70, the portions of the bearings within the tubular portion 69 being provided with annular rounded beads 71 71, said beads being the only portions of the bearings which bear against the tubes or cylinders 69. Arranged 120 between the inner ends of these bearings 70 is a pulley 72, said pulley being mounted fast on a long hub 73, which is arranged within the bearings 70. The outer end of one of the tubes or cylinders is closed by means of a cap-nut 74, and the outer end of the other tube or cylinder 69 has connected thereto the threaded inner end of the tubular dental-engine arm 75, which arm forms a casing or covering for a rigid shaft 76, one end of said shaft extending through the long hub 73 of the pulley and being provided with an elongated groove 77, which receives the inner end 130 of pin 78, which pin extends through the pul-

ley and through the hub 73, and thereby unites the pulley to the hub and also to the shaft 76. The pulley 72 is connected to any of the pulleys 44 of the motor-shaft by means 5 of the usual endless belt 78. The shaft 76 has connected to its outer end the usual flexible shaft, (not shown,) which extends to and has connected therewith the dental-engine tool, so that when the pulley 72 is rotated by 10 means of the belt 78 the shaft 76 and the flexible shaft connected thereto, as well as the dental tool, are rotated, as is common in this class of machines. The flexible shaft for the tool is incased by the usual flexible arm or 15 sheath 79.

The tubes or cylinders 69 have extending upwardly from the lower portions thereof pins 80 80, said pins engaging grooves 81 81 in the tubular bearings 70. These pins prevent 20 the tubular bearings 70 from rotating in the plane of the rotation of the pulley.

The bearings 70 are an important feature of my invention, inasmuch as they provide self-aligning bearings for the shafts 76 of the 25 pulley 72. If the bearing for the shaft 76 was simply formed by holes in the arms of the yoke 65 and said holes should happen to be out of true, the shaft would necessarily also be thrown out of true. In my improved 30 construction, however, by providing the bearing-sleeves 70, having the beads 71 there-around, no matter if the bores of the cylinders 69 are not exactly true the shafts 76 will nevertheless be true, inasmuch as the bearing-sleeves 70 will rock slightly on the beads 71 as fulcrum. This construction also possesses 35 an advantage after the machine has been put together and in use. When there is a tight pull on the belt, there is a downward strain, 40 with a tendency to spread the arms of the yoke apart. Under these conditions if the shaft 76 had its bearings merely in openings in the ends of the yoke-arms there would necessary be a binding. In my improved construction, however, even though a tight pull 45 on the belt should cause a downward strain on the arms of the yoke and a spreading of such arms apart, there would be no binding of the shaft, inasmuch as the bearing-sleeves 50 70 would rock on the beads 71 and said bearing-sleeves would therefore align the shaft.

What I claim as my invention is—

1. In a dental engine, the combination, of an upwardly-extending sleeve, a dental-engine standard fitting therein, said standard having a threaded opening at one end, and a rod having a threaded portion engaging the threaded opening, whereby as a rod is turned the standard is raised or lowered.
2. In a dental engine, the combination, of an upwardly-extending sleeve, a two-part standard, the sections thereof telescoping, and the lower section fitting in the sleeve, and the end of said lower section having a 65 threaded opening, a rod having a threaded portion engaging said opening, and a spring interposed between the lower end of the up-

per section of the standard and a fixed point of the lower section of said standard.

3. In a dental engine, the combination, of 70 a standard, a slotted arm fitting in the standard, a slidable sleeve surrounding the arm and the standard, a dental-engine head pivoted to the arm and provided with a depending stem, which stem, when the head is turned 75 upwardly, is adapted to fit in the slot of the arm, and means acting on the sleeve in order to hold said sleeve in a position to surround the depending stem of the head, when said stem is in the slot of the arm, but permitting 80 said sleeve to be slid out of engagement with the stem so as to allow said stem to be turned out of the slot.

4. In a dental engine, the combination, of 85 a standard, a slotted arm having a depending reduced portion, the latter fitting the standard, a slidable sleeve surrounding the arm and the standard, a dental-engine head pivoted to the arm and provided with a depending stem, which stem, when the head is turned 90 upwardly, is adapted to fit in the slot of the arm, and a spring surrounding the reduced portion of the arm, and bearing at one end against a fixed portion of the sleeve and at its opposite end against the standard. 95

5. In a dental engine, the combination, of 100 a standard, a slotted arm fitting in the standard, a slidable sleeve surrounding the arm and the standard, the upper end of said sleeve being rounded or beveled, a dental-engine 105 head pivoted to the arm and provided with a depending stem, one corner of the lower end of said stem being rounded or beveled, and said stem, when the head is turned upwardly, adapted to fit in the slot of the arm, and 110 means acting on the sleeve in order to hold said sleeve in position to surround the depending stem of the head when said stem is in the slot of the arm, but permitting said sleeve to be slid out of engagement with the 115 stem so as to allow said stem to be turned out of the slot.

6. In a dental engine, the combination, of 120 a dental-engine head, the arms thereof provided at their ends with tubes or cylinders, 115 bearing-sleeves, said sleeves extending into the tubes or cylinders, rounded beads forming normally the only points of contact between the sleeves and the bores of the cylinders, a shaft extending into the bearing-sleeves, and 125 a pulley connected fast to the shaft.

7. In a dental engine, the combination of 130 a dental-engine head, the arms thereof provided at their ends with tubes or cylinders, bearing-sleeves, said sleeves extending into the tubes or cylinders, rounded beads forming normally the only points of contact between the sleeves and the bores of the cylinders, a shaft extending into the bearing-sleeves, a pulley connected fast to the shaft, and means for preventing the bearing-sleeves from turning in a direction parallel to the plane of rotation of the pulley.

8. In a dental engine, the combination, of

a dental-engine head, the arms thereof provided at their ends with tubes or cylinders, bearing-sleeves provided with rounded beads, said sleeves extending into the tubes or cylinders, and the rounded beads thereof contacting with the interior of said tubes or cylinders, and said bearing-sleeves also provided with grooves or recesses, a shaft extending into the bearing-sleeves, a pulley connected fast to the shaft, and pins extending from the

tubes or cylinders and engaging the grooves of the bearing-sleeves, whereby said sleeves are prevented from rotating in the same plane of rotation as the pulley.

In testimony whereof I affix my signature 15 in presence of two witnesses.

FREDERICK H. BERRY.
